UNITED STATES PATENT OFFICE.

CLARK H. RIGGLE, OF PLEASANT VALLEY, OHIO.

FISH-PLATE.

SPECIFICATION forming part of Letters Patent No. 726,760, dated April 28, 1903.

Application filed December 9, 1902. Serial No. 134,540. (No model.)

To all whom it may concern:

Be it known that I, CLARK H. RIGGLE, a citizen of the United States, residing at Pleasant Valley, in the county of Muskingum and State 5 of Ohio, have invented new and useful Improvements in Fish-Plates, of which the following is a specification.

My invention relates to improvements in fish-plates for railroad-joints and means for 10 securing them; and the object of the same is to construct a device which will not work loose and will firmly secure the track against spreading.

The simple and novel construction employed 15 by me in carrying out my invention is fully described and claimed in this specification and illustrated in the accompanying drawings, forming a part thereof, in which—

Figure 1 is a transverse section of a track 20 equipped with my device. Fig. 2 is a plan view of the same. Fig. 3 is a detail of the fish-plates. Fig. 4 is a detail of the clamp.

Like numerals of reference designate like 25 parts in the different views of the drawings.

In the drawings are shown a rail 1, which forms one side of a track, and two abutting rails 2, which form the other side of the track. The track is supported on ties 3, and the rails 2 have apertures 4 in the ends thereof to accommodate studs 5, formed on a fish-plate 6. The studs 5 pass through the apertures 4 and engage a fish-plate 7, having apertures 8 therein. A clamp 9 secures the plates 6 and 7 together and comprises a stationary jaw 10 and a sliding jaw 11, mounted in guides 12 and actuated by an adjusting or clamping screw 13, bearing on the rear end thereof. The guides 12 are formed on a head 14, which bears a threaded neck 15, which is engaged 30 by a turnbuckle 16, which also engages a threaded shank 17, bearing a claw 18, which engages the rail 1.

After the rails 2 are laid the fish-plates 6 and 7 are put on, after which the jaws 10 and 45 11 are set to grasp them and are firmly clamped by means of the screw 13. The claw 18 is

then engaged on the rail 1 and the turnbuckle tightened. It is now evident that by my device the fish-plates are securely held and the track held against spreading.

I do not wish to be limited as to details of construction, as these may be modified in many particulars without departing from the spirit of my invention.

Having thus described my invention, what 55 I claim as new, and desire to secure by Letters Patent, is—

1. In a device of the class described, the combination of a head bearing a fixed jaw and a sliding jaw, means for clamping said jaws 6e to secure fish-plates, a threaded shank bearing a claw, and a turnbuckle connecting said head and said threaded shank, substantially as described.

2. In a device of the class described, the 65 combination of a head bearing a fixed jaw and a sliding jaw coöperating with said fixed jaw, means for securing said jaw against movement, a threaded shank connected to said head, a claw provided with a threaded shank and 70 designed to engage one rail while said first-mentioned jaw engages the other rail of a track, and a turnbuckle engaging said shanks, substantially as described.

3. In a device of the class described, a fish- 75 plate bearing studs designed to fit apertures in abutting rails, a fish-plate having apertures fitting over said studs, a head provided with jaws engaging and securing said fish-plates, and a claw bearing a shank adjustably 80 connected to said head, said claw being designed to engage the rail on the other side of the track from said fish-plate, substantially as described.

In testimony whereof I have hereunto set 85 my hand in presence of two subscribing witnesses.

CLARK H. RIGGLE.
